US0D1071224S

(12) **United States Design Patent** (10) **Patent No.:** **US D1,071,224 S**
(45) **Date of Patent:** **** Apr. 15, 2025**

(54) **PORTABLE LABORATORY**

(71) Applicant: **P³LAB**, Ottignies-Louvain-la-Neuve (BE)

(72) Inventor: **Pierre Martin Jack Gérard Daye**, Braine-l'alleud (BE)

(73) Assignee: **P³LAB**, Ottignies-Louvain-la-Neuve (FR)

(**) Term: **15 Years**

(21) Appl. No.: **29/849,605**

(22) Filed: **Aug. 12, 2022**

(51) **LOC (15) Cl.** **24-02**

(52) **U.S. Cl.**

USPC **D24/172**

(58) **Field of Classification Search**

(57) **CLAIM**

The ornamental design for a portable laboratory, as shown and described.

DESCRIPTION

FIG. 1 is a perspective view of a portable laboratory, showing my new design;

FIG. 2 is a front view thereof;

FIG. 3 is a right side view thereof;

FIG. 4 is a left side view thereof;

FIG. 5 is a rear view thereof;

FIG. 6 is a bottom view thereof; and,

FIG. 7 is a top view thereof.

The broken lines depict portions of the portable laboratory that form no part of the claimed design.

1 Claim, 7 Drawing Sheets
